Primary Examiner—Raphael Barkai*Assistant Examiner*—Mitchell I. Siegel**[57] CLAIM**

The ornamental design for an iron golf club head, as shown and described.

DESCRIPTION

FIG. 1 is a front elevational view showing my new design; FIG. 2 is a top elevational view of FIG. 1;

FIG. 3 is a front elevational view of a second embodiment of the invention;

FIG. 4 is a top elevational view of FIG. 3; and,

FIG. 5 is a left end view of FIG. 1.

The undisclosed left side of the second embodiment is identical to that disclosed in the first.

The undisclosed bottom and back of both embodiments form no part of the claimed design.
